MANIFOLDING APPARATUS

Filed Jan. 9, 1928

Fig. 1

UNITED STATES PATENT OFFICE.

ALFRED OSER, OF VIENNA, AUSTRIA.

MANIFOLDING APPARATUS.

Application filed January 9, 1928, Serial No. 245,549, and in Austria March 2, 1927.

This invention relates to an apparatus for manifolding in general and particularly for duplicating bookkeeping entries.

A process is known for manifolding such entries, according to which simultaneously with the original entry a mirror or reversed copy thereof is prepared, which is capable of giving off part of its color or ink to another paper and which is transferred line by line to cards or sheets by exerting a powerful pressure on the front face of the stencil. If before making the impression, the cards are moistened, it is possible to obtain numerous clearly legible copies with a single 15 stencil, but it is necessary in that case to exert a considerable pressure in printing.

In spite of its advantages for bookkeeping purposes, this process has not been largely adopted in practice as up to now an apparatus did not exist which could be manipulated in a simple manner, manufactured at a small cost and yet would enable the work to be done quickly without too much effort.

The apparatus according to this invention 25 solves this problem. It substantially consists in a slide adjustable in the direction of height of a bed or plate, which is formed into a device for clamping or fixing one longitudinal edge of the stencil, a moistening 30 device slidably mounted in a cross-guide of the bed-plate and intended for moistening the sheet on which the manifold impression is produced, and a pressure or printing member, also movable in a cross-guide, for 35 re-producing the impression. The moistening device and the pressure or printing member are preferably mounted on a fork, between the branches or prongs of which is placed the stencil, owing to which the 40 moistening and the printing may be effected in a single operation.

A construction according to the invention is illustrated by way of example in the accompanying drawings:

Figure 1 shows the apparatus in perspective.

Figure 2 is an elevation, partly sectional, of the most essential elements of the apparatus at an enlarged scale.

Figure 3 a cross-section according to the line 3—3 of Figure 2 and

Figure 4 a sectional view of the line spacing device.

1 is the base plate of the apparatus with 55 a bar or rail 2 secured edgewise thereto and a slidably mounted rail or slide 3, the distance between these two rails being equal to the width of the cards 4, on which the impressions are to be produced. 5 are two 60 marks indicating the distance of two lines for the purpose of facilitating the line adjustment of the card.

The stencil 6 may for instance be made by means of a typewriter, carbon paper being inserted so that its coloring side touches the back of the sheet, on which the types are striking, whereby simultaneously with the writing on the front of this sheet a mirror or reversed copy of this writing is obtained on its back.

The slide 3 consists of two parts lengthwise pivotally connected by means of hinge-joints 7 and is slidably mounted in a guide 8 of the base plate. Between the said two 75 parts of the slide, which in Figure 1 of the drawing are shown in the open position, the stencil 6 is to be fixed. For this purpose the one part of the slide is preferably provided with pins 9 and the stencil with corresponding perforation. A line spacing device of known construction, as shown in Figure 4, may be provided, which is operated by the handle 10 and which prevents the slide from being moved to fractions of 80 the height of a line.

11 are guide rods, fixed to a head 12 and at their other ends connected to one another by means of a frame 13 provided with a pressure button 14.

The rods, or more exactly expressed their head 12, are journalled by a joint 15 to a support 26 of the base plate, so that the rods can turn up into an oblique position shown in Figure 1 under the action of a spring 12^a 95 placed underneath of the base plate and engaging with a downwardly extending part of the head 12.

The rods 11 are guiding the support 18 of the pressure roller 16, which is pressed down 100

- by springs 17. A rod 19 is secured parallel to the rods 11 to the guiding body of the said roller support, is guided in the frame 13 and at its outer end provided with a handle 20.
- 5 To the latter a resilient (steel) band 21 is bodily connected or secured so as to extend inwardly parallel to the rods 11. This elastic band carries at its free end a wiper 22 of an absorbent material for the moistening.
- 10 The wiper is inserted in an aperture of the bottom of a little tank or receptacle 23, which is carried by the end of the band and can be closed up by a cover 24. For the purpose of maintaining the entire body of rods and
- 15 band against the action of the spring 12^a in the lowered position, the lower part of the frame 13 may be held clamped by a screw 25.

The rod 19 carrying the pressure roller 16 and the resilient band 21 carrying the wiper 20 are thus forming a fork, between the branches or prongs of which is placed the stencil fastened to the slide 3 on its one edge. By a suitable movement of the slide 3 the stencil is brought into such a position, that the pressure roller 16 is situated in the line to be reproduced. The line of the card 4, on which the entry is to be copied, is then set by means of the marks 5. The frame 13 is now pressed down, so that the roller 16 is 30 pressed downward on the stencil, whilst the wiper 22 is in this position, owing to the resiliency of the band 21, pressed against the card 4. If now by means of the handle 20 roller and wiper are pulled along the guiding rods 11, the set line of the card 4 is moistened and immediately thereafter the writing of the stencil 6 is transferred to the card by the strong pressure of the spring controlled roller following the wiper. When 40 the roller has arrived at the end of the line, the pressure on the frame 13 is released and the fork pushed back, so that all parts will again be in the position as shown in Fig. 1. The card 4 is therupon replaced by another 45 one, on which the same entry is to be made.

In the operation of printing it may happen, that the roller 16 runs to the edge of the stencil and the wiper 22 is moved beyond the edge of the card 4. The stencil will 50 thus not be supported any more by the band 21 and for moving the printing device back into its original position it should be necessary to re-introduce it between the roller 16 and the band 21. In order to avoid such 55 necessity needle-like little rods or rails 28 are secured to the frame 13, which are supporting the stencil also in the case of the wiper trespassing the edge of the card.

For the purpose of making the already 60 transferred lines of the stencil, there may be provided adjustable needles 27 on the support 26, to which the head 12 is journaled. When the latter is pressed down, these needles are by the action of a plate lowered 65 and will be driven through the stencil, the

perforations of which are indicating, that the respective lines have already been copied.

The line spacing device (Fig. 4) consists of a bar 30 suitably guided underneath and in the direction of the slide 3. At the one end of this bar a spring controlled pawl 31 is provided, which engages consecutively with suitable spaced holes 32 of the base part of the slide 3 and at its rear end it is 75 by means of a link 33 connected to the handle 10, by which the line spacing device is actuated.

The apparatus according to this invention is particularly adapted for manifolding line 80 by line, it may, however, also be used as ordinary duplicating apparatus reproducing the writing on the entire surface of the stencil in one operation. For this purpose it is only necessary to make the length of the 85 roller 16 and of the wiper equal to the height of the stencil.

What I claim is:

1. A manifolding apparatus consisting of a base plate, a device for fixing the stencil, a 90 wiper, a member adapted for exerting a pressure on the stencil and guides for the wiper and the said pressure member.

2. A manifolding apparatus consisting of a base plate, a device for fixing the stencil, a 95 guide for the fixing device, a wiper, a member adapted for exerting a pressure on the stencil and guides for the wiper and the said pressure member.

3. A manifolding apparatus consisting of a base plate, a slide adapted for fixing the stencil, which slide is composed of two parts, a guide for this slide, a wiper, a member adapted for exerting a pressure on the stencil and guides for the wiper and the 100 said pressure member.

4. A manifolding apparatus consisting of a base plate, a device for fixing the stencil, means for shifting the stencil fixing device for the space of a line, a wiper, a member adapted for exerting a pressure on the stencil and guides for the wiper and the 105 said pressure member.

5. A manifolding apparatus consisting of a base plate, a device for fixing the stencil, a wiper, a pressure member and guides for the wiper and the pressure member adapted to be turned around a pivot.

6. A manifolding apparatus consisting of a base plate, a device for fixing the stencil, a wiper, a pressure member, guides for the wiper and the pressure member adapted to be turned around a pivot and a spring 115 adapted to keep the guides in oblique position.

7. A manifolding apparatus consisting of a base plate, a device for fixing the stencil, a wiper and a pressure member, a fork on the branches of which the wiper and the 120

125

130

pressure member are placed and guiding means for this fork.

8. A manifolding apparatus consisting of a base plate, a device for fixing the stencil, a wiper, a pressure member, guides for wiper and pressure member, which guides are pivotally connected to the base plate, and means for anchoring the guides on the base plate.

10 9. A manifolding apparatus consisting of a base plate, a device for fixing the stencil, a fork having two resilient prongs, a wiper mounted on the same on a resilient prong of this fork, a pressure member carried by the 15 other branch of said fork and guides for the wiper and the pressure member.

10 10. A manifolding apparatus consisting of a base plate, a device for fixing the stencil, a wiper, a receptacle with an aperture 20 closed up by the said wiper, a pressure member and guides for wiper and pressure member.

25 11. A manifolding apparatus consisting of a base plate, a device for fixing the stencil, a wiper, a pressure member, journalled guides for them, a support secured to the base plate, to which support the guides are journalled, and needles adjustably mounted on the support and placed in the path of the 30 turning guides.

35 12. A manifolding apparatus consisting of a base plate, a device for fixing the stencil, a fork having two prongs, a wiper and a pressure member carried by the prongs of said fork, guides for the wiper and the pressure member and needles on the guides for supporting the stencil.

40 13. A manifolding apparatus consisting of a base plate provided with two rails, the distance of which is equal to the width of the cards, on which the copies are to be impressed, means, by which one of these rails is adapted for fixing the stencil, a wiper, a pressure member and guides for wiper and 45 pressure member.

50 14. A manifolding apparatus consisting of a base plate with a line mark, a device for fixing the stencil, a wiper, a member adapted for exerting a pressure on the stencil and guides for the wiper and the said pressure member.

In testimony whereof I have affixed my signature.

ALFRED OSER.
